RIPPING SCISSORS

Lewis A. Amis, Dallas, Tex.

Application September 18, 1944, Serial No. 554,641

6 Claims. (Cl. 30—261)

This invention relates to shears or scissors and has particular reference to new and useful improvements in ripping shears.

The objects of the invention are, first: to provide ripping shears or scissors having means on one of the blades thereof for detachably retaining a cutting element, preferably a razor blade, which is so disposed in relation to the companion blade of the shears as to present an efficient cutting edge to the stitches of a seam to quickly sever them without injury to the fabric; second: to provide an adjustable spring and latching means therefor to maintain predetermined spacing of the handle elements of the scissors under tension of the spring, combined with means for limiting the relative displacement of the handle elements under such spring tension, to correspondingly control the movements of the cutting blades, to thereby facilitate the ripping operation; third: to provide on the tensioning spring, means for holding the same in operative and inoperative positions.

With the foregoing objects as paramount, the invention has further reference to certain features of accomplishment which will become apparent as the description proceeds, taken in connection with the accompanying drawing wherein:

Figure 1 is a side elevational view of a pair of ripping shears constructed according to the present invention, showing the latching means inoperatively disposed.

Figure 2 is a similar view but showing the spring in operative position to effect corresponding position of the cutting blades.

Figure 3 is a fragmentary perspective view showing the spring in the same position as illustrated in Figure 2.

Figure 4 is a vertical section taken on line 4—4 on Figure 2.

Figure 5 is a perspective view of the spring perse.

Figure 6 is a vertical sectional view taken on line 6—6 on Figure 2 and.

Figure 7 is a perspective of the stirrup employed for limiting the tensional displacement of the latching spring.

Continuing with a more detailed description of the drawing, reference is primarily made to Figure 1 wherein numeral 10 denotes the handle integral with the conventional blade 11 while numeral 12 denotes the handle integral with the improved blade mounting 13 which latter is so designed and constructed as to accommodate a detachable cutting blade 14.

The detachable cutting blade 14 consists preferably of a conventional safety razor blade, probably of the double edge variety broken in half. Obviously a detachable blade may be especially designed for this purpose but inasmuch as great quantities of razor blades are cast off and wasted, they may continue to serve a useful purpose when applied as described herein. As a means for attaching the blade 14 to the blade mounting 13, the latter is ground to produce a recess 15 to accommodate the blade. It will be noted in Figure 6 that the plane of this recess is inclined a slight degree in relation to the confronting face of the companion blade 11 so as to properly dispose the blade 14 in cutting or shearing relation to the effective edge of the blade 11. To secure the blade 14 to the mounting 13, a spring clip 16 of circuitous formation extends a short distance axially of the mounting 13 and whose ends extend through and are anchored from the opposite side of the blade mounting 13 at 17 (Figure 6). The spring clip 16 lies flush against the recess 15 of the blade mounting 13 so that when the blade 14 is inserted thereunder, it will impose sufficient pressure thereagainst as to hold the latter in place. Supplementing this pressure as a holding means for the blade, relatively spaced projections 18, extending from the back of the blade and between which the ends of the clip 16 extend, are effective to prevent longitudinal displacement of the blade 14. These projections are usually present on each half of a blade which has been broken in two, although they may be especially formed on a blade designed for use with the shears of the invention.

In using the shears for ripping seams, it is preferred that the blade 11 be held in such relationship with the blade mounting 13 that the cutting edge of the blade 14 will lie angularly across the effective edge of the blade 11 in the approximate relationship shown in Figure 2, better results being had when such relationship of the cutting blades is maintained under spring tension. To accomplish this, a leaf spring 19 is provided and shown in detail in Figure 5. This spring has a slot 20 disposed longitudinally thereof, through which is passed a screw 21, by which the spring is secured for longitudinal displacement to a boss 22 formed on the handle element 10 of the blade 11. Formed on one edge of the spring 19 and bent to overlie one face thereof is an arm 23. The purpose of this arm is to hold the spring 19 in adjusted position, it being apparent that when disposed on one side of the head 55 of the screw 21, the spring is in operative position

and when disposed on the opposite side of this screw, the spring is in inoperative position. This is exemplified in Figures 1 and 2 showing respectively operative and inoperative positions of the spring. The inherent resiliency of the arm 23 enables it to yield to the head of the screw 21 as the spring 19 is pivoted from one to the other of its two positions. The arm 23 extends slightly beyond the edge of the spring 19 and hence may serve as a handle to effect manipulation of the spring, as described.

The inner end of the spring 19 is turned under the main body portion thereof and is bifurcated to form a slot 24 parallel with the axis of the spring. In latched position of the shears, the slot 24 of the spring receives the head 25 of a screw or other protuberance 26, extending upwardly from a boss 27, formed on the handle element 12 of the blade mounting 13.

When the spring 19 is in engaged relationship with the protuberance 26, as shown in Figures 2 and 3, the cutting elements of the shears are disposed in the preferred position for ripping but in order to limit the relative displacement of the blades, the hooked end of the spring 19 is restricted in its travel by means of a stirrup 28, shown in detail in Figure 7. This stirrup consists of a U-shaped member, whose legs are secured on either side of the handle element 10, while the lower portion thereof embraces the end of the spring, as shown. Longitudinal displacement of the spring 19 is so limited by the slot 20 that at no time is the hooked end of the spring completely free from the stirrup 28. When in latched position with the protuberance 26, the tip end of the spring extends within the stirrup 28 and its movement is limited to the length of the stirrup and consequently movements of the cutting blades are correspondingly limited.

The ripping operation is usually performed by inserting the fingers through the openings 29 in the handle element 10 to guide the shears into the stitches of the seam, allowing the handle element 12 to move freely under tension of the spring 19. In order to prevent the cutting elements from being closed entirely, the spring 19 projects rearwardly, when in latched position so that its rear end 30 will lie between the handle elements 10 and 12. The end 30 of the spring is shown as being built up and it is apparent that the thickness thereof may be increased or decreased, depending upon the desired spacing of the edges of the cutting elements.

When it is desired to use the shears in a conventional manner, the spring 19 is moved forwardly, bringing the resilient arm 23 thereof over the head of the screw 21 and in so doing, the slotted end of the spring is disengaged from the head 25 of the protuberance 26. The handle elements 10 and 12 may be actuated freely without restriction.

Manifestly, the construction as shown and described is capable of some modification and such modification as may be construed to fall within the scope and meaning of the appended claims is also considered to be within the spirit and intent of the invention.

What is claimed is:

1. A ripping scissors including a pivoted blade and a razor blade mounting, each having a handle element, said blade mounting having a longitudinal recess defining a ledge along its top and receiving a razor blade, a tortuous spring disposed longitudinally on the face of said recess, having its ends embedded therein and bearing tensionally thereagainst to retain said razor blade, means limiting the relative displacement of said scissors blade and razor blade mounting, said means consisting of a slotted leaf spring mounted upon and adjustable longitudinally with respect to the handle element of said scissors blade, means carried by the companion handle element for engaging the slot of said spring and means for limiting the displacement of said spring as said handle elements are actuated.
2. A ripping scissors including a pivoted scissors blade and a blade mounting, each having a handle element, a detachable blade secured in said blade mounting whose cutting edge coincides with that of said scissors blade, a leaf spring having a slot intermediate its ends and mounted for longitudinal sliding movement on the handle element of said scissors blade and further having a hooked and slotted end, means carried by the companion handle element engaging the slot in the hooked end of said spring to resist opening movement of said blade and blade mounting and means embracing and limiting the movement of the hooked end of said spring.
3. A ripping scissors including pivoted arms, one of which defines a cutting blade, the other detachably carrying a complementary cutting blade, both arms having handle elements, spring means adjustably mounted on one of said handle elements and engageable with means on the companion handle element for yieldingly resisting the opening movement of said arms and means for restricting the movement of said spring means to accordingly restrict the displacement of said arms.
4. A scissors comprising a hinged blade and blade mounting, a blade detachably secured to said blade mounting, handle elements for said blade and mounting, spring means attached to one handle element and engageable at one end with means on the companion handle element to yieldingly resist opening of said blade and mounting, means to limit movements of said spring means to correspondingly limit the displacement of said blade and mounting and means to limit the closing action of said blade and mounting.
5. A scissors including pivoted, complementary cutting members, one of which is detachable, handle elements for each of said members, spring means on one of said elements engageable with means on the companion element for yieldably resisting opening action thereof and further adapted to prevent full closing of said cutting members.
6. The structure as described in claim 5, further defined in that the spring means is longitudinally adjustable to release the cutting members for conventional operation as scissors.
